FIG. 2

UNITED STATES PATENT OFFICE

CLAIR W. PHILLIPS, OF LYNCH, KENTUCKY

ROTARY STEAM ENGINE

Application filed April 6, 1928. Serial No. 267,928.

This invention relates to a rotary engine of the reversible type and which is designed to be used with steam, the general object of the invention being to provide a circular 5 casing having an outlet and a pair of inlet ports, with a blade carrying rotor eccentrically arranged in the casing, with means for projecting the blades as the rotor moves out of contact with a part of the casing and 10 valve means for controlling the inlet ports so that the rotor can be made to rotate in either direction.

Another object of the invention is to provide pump means for lubricating the bearings of the rotor.

This invention also consists in certain other features of construction and in the combination and arrangement of the several parts, to be hereinafter fully described, illustrated in the accompanying drawings and 20 specifically pointed out in the appended claim.

In describing my invention in detail, reference will be had to the accompanying drawings wherein like characters denote like or 25 corresponding parts throughout the several views, and in which:—

Figure 1 is a sectional view through the improved engine.

Figure 2 is a section on line 2—2 of Figure 1.

Figure 3 is a section on line 3—3 of Figure 1.

Figure 4 is a view of one of the blades of 35 the rotor.

Figure 5 is a sectional view showing a modified form of blade.

Figure 6 is a sectional view of the lubricating pump.

Figure 7 is a detail sectional view of a 40 part of the outlet for said pump.

Figure 8 is a view of the valve member.

In these drawings, A indicates a circular casing which is formed of the two side plates 45 1 and the rim 2, each side plate having an annular projection 3 on its inner face adjacent the periphery of the plate, the side of the projection being beveled and its outer end being flat to form a seat for the rim 2 which is bolted to the side plates. The rim

is formed with an outlet 4 and a pair of inlet ports 5, these inlet ports passing through a flattened part of the casing to which is attached a valve housing 6 having its lower part 6' bolted to its upper part. This housing is formed with the passages 7 which form continuations of the ports 5 and these passages lead to the inlet 8 at the outer or lower end of the housing. A pair of slide valves 9 controls the passages 7, these valves being 55 connected together by a rod 10 so that they will move in unison and the ports 11 in these valves are so arranged that when one port is registering with one of the passages 7, the other port is moved out of register with the 60 opposite passage so as to close the same.

A lever 12 is pivoted in a part of the housing and is connected with the rod 10 and a yoke member 13 is slidably arranged on the housing and carries a pin 14 at its 70 central part which passes through a slot in the lever so that by moving the yoke member through means of its handle 15, the lever will be rocked in one direction or the other to shift the valves to open either passage 7 75 and close the other passage.

A rotor 16 is eccentrically arranged in the casing, with a portion thereof contacting with the bottom of the casing so that the rotor and casing form a crescent-shaped chamber, the ends of which are in communication with the ports 5. The trunnions 17 of the rotor are journaled in the bearing bosses 18 formed on the side plates 1, these bosses being eccentrically arranged, as shown. A 80 plurality of blades 19 are movably arranged in the radial slots 20 formed in the rotor and a ring 21 is eccentrically arranged on the inner wall of each end plate, these rings engaging the ends of the inner edges of the blades and acting to keep the outer edges of the blades against the rim of the casing, as shown in Figures 1 and 2. The outer ends of the blades have their ends beveled to engage the beveled faces of the projections 3 and each blade is formed with a tip 22 preferably of bronze which is suitably connected with the blade. Figure 4 shows one way of attaching the tip to a blade, but Figure 5 shows the preferred form. This 85 90 95 100

figure shows a strip 23, preferably of bronze, fastened to the end of the blade by the screws 24.

From the foregoing it will be seen that when steam or other expansible fluid is introduced into the casing through an inlet 5, it will enter the pockets formed by the blades, the rotor and the casing and thus exert pressure against the blades to cause the rotor to rotate and the direction of this rotary movement will be away from the inlet port which is open. For instance, in Figure 1, the rotor will revolve in an anti-clockwise direction as the right hand inlet passage 15 is open, but if this passage is closed and the left hand passage opened by the valve, the rotor would revolve in the opposite direction. As the blades move toward the bottom of the casing, they will be forced inwardly by the rim of the casing, the eccentrically arranged rings 21 permitting this movement and then as the blades move upwardly with the rotor, they are forced outwardly and thus kept in contact with the rim of the casing by said rings 21, as clearly shown in Figure 1.

I also provide pumps for lubricating the bearings, each pump comprising a casing 25 connected with each boss 18 and having a cylinder 26 therein in which is arranged a piston 27 which has its upper end pivoted to an eccentric strap 28 engaging an eccentric groove in the trunnion 17 so that as the trunnion rotates, the eccentric strap will reciprocate the piston 27 to cause it to draw oil from the casing into the cylinder through the holes 29 on its upward stroke and to force said oil from the cylinder on its downward stroke through the passage 30 into the bearing. A check valve 31 is arranged in said passage 30.

This motor can be arranged at any angle and will start with a full load and it can be caused to operate in either direction by moving the valves through the yoke 13.

It is thought from the foregoing description that the advantages and novel features of my invention will be readily apparent.

It is to be understood that I may make changes in the construction and in the combination and arrangement of the several parts, provided that such changes fall within the scope of the appended claim.

What I claim is:—

55. An engine of the class described, comprising a circular casing, a rotor eccentrically arranged therein and supported for rotation, radially arranged blades slidably carried by the rotor, the periphery of the rotor and the 60 circumferential wall of the casing defining a crescent shaped chamber, the casing having an outlet port located between the ends of said chamber, a valve casing mounted upon the under side of the casing and having 65 inlet passages communicating with the

ends of said chamber, whereby a motive fluid may enter the chamber at either end thereof to vary the direction of rotation of the rotor, the valve casing comprising separable connected sections and formed in the meeting faces of the two sections with matching horizontal recesses providing valve chambers, flat valve plates slidably mounted in said chambers and each provided near its outer end with an opening for registration with the respective one of the intake passages of the valve casing, a rod extending between and connecting the relatively adjacent ends of said plates, rack arms pivotally mounted at their lower ends within the valve casing and having longitudinal slots therein, below their upper ends, pins extending from opposite sides of the said rod and engaging in the slots, whereby, when the arm is rocked about its pivot, shifting adjustment of the valves will be effected to open one of the inlet passages and close the other inlet passage, a frame disposed exteriorly of the valve casing and including side members and connecting end members, means connecting the upper ends of the said arms pivotally with the side members of said frame, and a handle member upon one end of the frame.

In testimony whereof I affix my signature. 95
CLAIR W. PHILLIPS.
